UNITED STATES PATENT OFFICE

128,804

DESIGN FOR A FRONT FOR A NECKTIE HOLDER OR OTHER SIMILAR ARTICLE OF JEWELRY

Charles Silverman, Providence, R. I.

Application April 30, 1940, Serial No. 92,042

Term of patent 3½ years

To all whom it may concern:

Be it known that Charles Silverman, a citizen of the United States, residing at Providence, in the county of Providence and State of Rhode Island, has invented a certain new, original, and ornamental Design for a Front for a Necktie Holder or Other Similar Article of Jewelry, of which the following is a specification, reference being had to the accompanying drawing, forming part thereof.

Fig. 1 is a front elevation of a front for a neck-tie holder or other similar article of jewelry embodying my new design.

Fig. 2 is a top plan view thereof.

The initial elements are interchangeable and the particular initials shown are merely illustrative.

I claim:

The ornamental design for a front for a necktie holder or other similar article of jewelry, substantially as shown and described.

CHARLES SILVERMAN.
